**LASTING MACHINE WITH ADHESIVE
APPLICATOR**

Henry v. d. Benken, West Roxbury, Mass., assignor to
Compo Shoe Machinery Corporation, Waltham, Mass.,
a corporation of Delaware

Filed June 7, 1966, Ser. No. 555,885

36 Claims. (Cl. 12—7)

ABSTRACT OF THE DISCLOSURE

A shoe lasting machine embodying a shoe support of smaller area than the bottom of the shoe to be lasted for supporting, bottom down, an upper and insole assembled on a last, an applicator in the form of a ring surrounding the support for engagement with the marginal edge of the insole, said applicator ring containing a groove to which liquid adhesive is adapted to be supplied for application to the margin of the insole, and a dual pump for delivering liquid adhesive from a reservoir of adhesive to the applicator ring while the latter is in contact with the margin of the insole and to return the adhesive left in the applicator to the reservoir when the applicator is lowered from the margin of the insole to permit wiping of the marginal edge of the upper into engagement with the adhesive-coated margin of the insole.

Recently there have been a number of attempts to incorporate in a lasting machine means for applying liquid or molten adhesive directly to the marginal edge of the insole prior to or during the tensioning of the upper and then while continuing to support the upper and insole assembly, separating the applicator from the insole appreciably to enable wiping the lasting margin into engagement therewith. The difficulty in such prior machines has been to supply sufficient adhesive to the margin to obtain an effective bond without overflow of the surplus adhesive onto the bottom support, wipers and other pertinent parts of the machine.

It is the purpose of this invention to provide a machine of the foregoing kind with means which enables applying adhesive in sufficient amount to obtain a good bond and removing the excess from the vicinity of the lasting instrumentalities; to provide means for supplying adhesive in liquid form to the insole by circulating it from a reservoir to an applicator and from thence back to the reservoir, thereby to reduce deterioration of the adhesive, to present fresh adhesive for each application, to prevent stagnation, and to prevent accumulation within the circulatory system; and to provide means which is clean, dependable and durable.

As herein illustrated, the aforesaid means comprises in conjunction with lasting instrumentalities and a rigid bottom support for supporting an upper and insole assembled on a last bottom down, an adhesive applying ring surrounding the bottom support. The upper surface of the bottom support and ring are collectively concave, corresponding substantially in contour to the bottom side of the insole, there is a space between the outer edge of the bottom support and the inner edge of the ring, and the ring contains a groove located in spaced relation to its outer edge and in confronting relation to the margin of the insole for receiving adhesive under pressure when the insole and ring are held engaged to effect deposition of adhesive on the insole. A receptacle is supported below the ring beneath the space between the ring and the bottom support for receiving the surplus adhesive which is displaced inwardly from the ring by the lasting operation and/or gravity to prevent accumulation on the bottom support and for receiving from the groove, the ends of which are connected thereto, the residual adhesive

2

left in the groove so that both the surplus and the residual adhesive may be returned to a reservoir for recirculation.

To enable accurate seating of the insole and ring, the latter is yieldably supported for translatory movement perpendicular to the bottom support and for angular movement about axes longitudinally and transversely of the bottom support. Adjustments are provided for controlling the extent of movement and the resistance to such movement. The support for the ring also supports a receptacle and the two are movable downwardly relative to the bottom support to enable lasting the marginal edge of the upper following the application of the adhesive to the insole.

The ring is supplied with adhesive and adhesive is exhausted from the receptacle by a pump which acts on one stroke to supply adhesive to the groove in the ring and on the other stroke to remove adhesive from the receptacle. The pump is located in a reservoir of liquid or molten adhesive and has two pistons which act in conjunction in one direction of movement to exhaust adhesive from the receptacle into one of a pair of chambers and to suck fresh adhesive from the reservoir into the other of the pair of chambers and in the other direction to return the exhausted adhesive to the reservoir and inject the fresh adhesive into the ring. The pump is driven by a pressure fluid operable motor and the latter may be controlled manually or automatically.

The invention will now be described in greater detail with reference to the accompanying drawings wherein:

FIG. 1 is an elevation, partly in section, of a shoe support and applicator for use in conjunction with a lasting machine for supporting an upper and insole assembled on a last preparatory to application of adhesive to the margin of the insole and lasting of the margin edge of the upper to the adhesive-coated margin of the insole;

FIG. 2 is a plan view of the support and applicator;
FIG. 3 is a vertical section taken on the line 3—3 of FIG. 2;

FIG. 4 is a vertical section taken on the line 4—4 of FIG. 2;

FIG. 5 is a plan view, partly in section, of a reservoir for holding molten adhesive which is to be delivered to the applicator;

FIG. 6 is a fragmentary elevation, partly in section, as seen from the lower side of FIG. 5;

FIG. 7 is a vertical section taken on the line 7—7 of FIG. 5; and

FIG. 8 is a horizontal section taken on the line 8—8 of FIG. 7.

The support and applicator herein illustrated comprise part of a lasting machine which, in conjunction with a hold-down of a suitable kind, not herein illustrated, support an upper and insole assembled on a last bottom side down for application of adhesive to the marginal edge of the insole, stretching of the upper material over the last and wiping the marginal edge of the upper into engagement with the adhesive-coated underside of the insole. In the machine with which the support and applicator are employed, the support is normally inclined so that when the upper and insole assembly are mounted on it with the heel end of the assembly toward the operator, the toe slopes upwardly and away from the operator toward the lasting instrumentality. For the sake of illustration, however, in order that the support may be centered on the drawing, the axis XX of the support is shown perpendicular rather than inclined.

The support comprises a rigid plate 10 secured to the upper end of a hollow post 12 adjacent lasting instrumentalities, which are here represented as lasting pinchers 14, and wiping means 16. The plate 10 supports the bottom from the tip of the toe to approximately the ball line and is of smaller area than the bottom of the insole so

that the latter projects laterally therefrom all the way around. The upper surface 18 of the support 10 is concave and of a configuration corresponding substantially to the curvature of the bottom side of the insole. The plate has a substantially rectangular rear portion (FIG. 2) and a triangular forward portion following, in general, the configuration of the forepart of the insole and contains in its upper surface a shallow recess 20 which reduces the supporting surface to relatively narrow, spaced parallel portions 22-22 at the rear end and converging portions 24-24 at the forward end which intersect at the toe. A tongue 26 is formed integral with the underside of the plate and this fits into a slot 28 formed in the upper end of an adaptor 30 by means of which the plate is mounted on the post 12. Threaded openings 32 are provided at the bottom of the recess 20 which extend through the tongue in which are mounted adjusting screws 34, the lower ends of which bottom on the slot 28 and provide for adjusting the level of the plate 10 on the post. The adaptor 30 has at its lower end a shaft 33 which sets into the upper end of the post 12 and is prevented from rotating therein by a pin 38 mounted diametrically therein, with its ends seated in slots 40 in the post.

The adhesive applicator comprises a ring 42 supported around the plate 10 which corresponds in configuration to the insole, that is the outer edge of the applicator corresponds in shape to the peripheral edge of the insole. The inner edge corresponds substantially in shape to the outer edge of the plate 10, but is spaced therefrom so as to provide an opening 44 between the applicator ring and the plate all the way around as clearly indicated in FIG. 2. The upper surface 46 of the ring is sloped and has a curvature which corresponds to the curvature of the bottom side of the insole at the margin and contains adjacent to but spaced from its outer edge a groove 48 which extends all the way around the ring, that is from the tip rearwardly along the opposite sides to substantially the ball line where it intersects transversely extending grooves 50, the inner ends of which are in communication with the space 44 between the ring and the plate. The groove 48 contains at the tip of the toe and at opposite sides of the tip and spaced rearwardly therefrom injection openings 52 through which adhesive is adapted to be injected to fill the groove. The grooves 50 at the rear ends of the groove 48 provide for draining off the adhesive in the groove 48 which will flow rearwardly along the groove by reason of the inclination of the ring.

Adhesive is supplied to the groove 48 and exhausted therefrom, as will appear hereinafter, to effect application of adhesive to the lasting margin of the insole while the ring is held against the insole. Following application of the adhesive to the insole, the ring 42 is lowered to permit the lasting margin of the upper to be wiped into engagement with the insole and during this period the surplus adhesive which is left in the groove and any surplus adhesive which is displaced inwardly from the groove during the wiping operation is collected in a receptacle 54 supported below the ring and returned therefrom to a reservoir. The receptacle 54 corresponds generally in shape to the ring and provides support for the latter, having for this purpose a flat upper edge 56 on which the lower side of the ring 42 rests and to which it is secured by bolts 58 which extend through suitable holes in the ring and are threaded into the upper edge of the receptacle. The receptacle has in its upper side a shallow trough 60 which underlies the space 44 situated between the plate and the ring and parts of the plate and ring, the inner side being constituted by a flange-like wall 62 bounding a central opening 64 through it through which the adaptor projects. The trough 60 provides for receiving the adhesive which flows inwardly from the groove 48 in the ring and into the space 44, so as to prevent accumulation of adhesive on the plate 10. At the rear end of the receptacle there is a longitudinally narrow, transversely wide and vertically deep well 66 into which the adhesive from the trough 60 flows and into which ad-

hesive from the groove 48 flows by way of the grooves 50. A strainer 68 is supported on a ledge 70 at the top of the well and an outlet opening 72 is provided at the bottom of the well into which is inserted a fitting 74 for receiving one end of a return pipe 76 by means of which adhesive which collects in the well may be extracted. The forward end of the receptacle 54 contains a passage 78, the lower end of which is provided with an opening 80 into which a fitting 82 is inserted by means of which one end of a delivery pipe 84 is connected to the passage for supplying adhesive thereto. The upper end of the passage 78 is provided with a fitting 86 which projects into the lower side of the ring 42 for conducting the adhesive from the passage 78 to the groove 48 in the ring. Heating elements 1 are mounted in cored openings in the walls of the receptacle.

The ring 42 is desirably supported so that it can adjust itself to the bottom of the insole and to this end the ring and the receptacle are yieldably mounted on the post 12 for movement relative to the plate 10 in translation and angularly about the longitudinal and transverse axes of the bottom. As illustrated, this movement is afforded by a bracket member 88 mounted on the post 12 comprising a sleeve-like portion 90 freely slidable on the post and supported at its lower end on the upper end of a coiled spring 92 encircling the post, the lower end of which bears upon a collar 94 fixed to the post. The translatory movement of the bracket on the post is limited by a slot 96 in the post and a pin 98 mounted in the sleeve and extending through the slot. A collar 100 threaded onto the upper end of the post, which is provided with a thread 102 for this purpose, enables controlling the height-wise position of the bracket 88 on the post.

The bracket 88 has a radially extending boss 104 at the left side, as shown in FIG. 1, which contains a vertical bore 106 in which is mounted the lower end of a rod 108. The upper end of the rod has on it a truncated ball 110 which is rotatably connected to the lower side of the receptacle by a cage 112 bolted to the bottom. At the right side of the bracket there are symmetrically disposed, transversely spaced sleeves 114-114 supported at the outer ends of diverging arms 116-116 and each sleeve contains a vertical opening 118 for receiving the lower end of a rod 120. The upper end of each rod is provided with a truncated ball 110 corresponding to that at the upper end of the rod 108 which is rotatably connected to the lower side of the receptacle by a cage 112. The rod 108 has a nut 122 on it which bears against the upper end of the boss 104 and thereby prevents downward movement of the rod relative to the bracket. Coiled springs 124 are mounted on the rods 120 between the upper ends of the sleeves 114 and the lower sides of nuts 126 threaded on these spindles. The nuts are adjustable on the rods to control the compression of the springs which permit downward displacement of the rods 120 in the sleeves 114 and hence downward displacement of the ring and receptacle relative to the bracket 88 about longitudinal and transverse axes to permit adjustment to the inclination of the bottom of the insole so that it is possible to secure a good seal between the upper surface of the ring and the lower surface of the insole even though the shoe assembly may be imperfectly clamped against the bottom support. The translatory movement permitted by the bracket 88 enables lowering the receptacle and ring from the lower surface of the insole sufficiently to permit lasting and suitable means is provided for effecting such lowering in the machine in question, although it is not illustrated herein.

As related above, adhesive is supplied to the applicator ring for each lasting operation and the surplus following 70 lasting operations is removed and returned to the source of supply which comprises a heated reservoir 128 (FIGS. 5 through 8) within which solid adhesive may be placed for melting and from and to which it is pumped by a pump 130 (FIG. 8). The reservoir 128 comprises a rectangular receptacle provided with an outer covering of insulation

132 at its bottom and sides and a cover 134 hinged at 136 over an opening 138 in the top. Suitable heating elements r_2 are embedded in the bottom for melting solid adhesive placed in the reservoir. The pump 130 is fastened to the bottom of the reservoir by bolts 140 of which two are illustrated. The bolts 140 are long enough so that when threaded into the bottom to hold the pump in place their upper ends 141 project above the normal level of the adhesive thus making it possible to remove them while the adhesive is still in a molten condition if it is necessary to remove the pump. The pump itself comprises a block 142 of generally rectangular configuration containing spaced parallel pump chambers 144 and 146 within which there are mounted pistons 148 and 150. The pistons 148 and 150 extend from the right end of the block 142 and are pivotally connected to a crankpin 152 fixed in one end of a link 153, the opposite end of which is pivotally connected to the lower end of a crankarm 154. The crankarm 154 extends upwardly from the bottom and is secured at its upper end to a shaft 156 journaled transversely of the reservoir in suitable bearings 157 in the walls with one end projecting laterally from the reservoir through the wall to which there is connected the upper end of a crankarm 160. The lower end of the crankarm 160 is provided with a crankpin 162 and this is pivotally connected to the forward end of a piston rod 164 projecting from one end of a motor cylinder 166. The opposite end of the motor cylinder 166 is pivotally mounted on a pin 168 secured to the wall of the reservoir. An adjustable screw 170, mounted on a bracket 172 opposite the distal end of the rod 164, provides means for limiting the stroke and correspondingly the stroke of the pistons. Thus, it is evident that by supplying fluid pressure to the motor cylinder 166, reciprocable movement can be imparted to the pistons 148 and 150. The pump block 142 is provided with a plurality of valves so that reciprocation of the pistons 148 and 150 on one stroke force a quantity of adhesive from the reservoir into the ring 42 and on the reverse stroke exhaust the surplus adhesive from the receptacle 54. The passages to and from the pump to the applicator comprise in the pump block the passage 170' and the passage 172' which have fittings 174' and 176' externally of the reservoir adapted to be connected respectively with the pipes 84 and 76. During movement of the pistons 148 and 150 from right to left, the piston 150 forces adhesive, which was drawn into the chamber 146 during the preceding movement from left to right, out through the valve V1 and from thence through passage 170', fitting 174' and pipe 84 to the ring 42. The valve V2 is closed during this time. Simultaneously the piston 148 discharges adhesive which was drawn into the chamber 144 during the previous movement from left to right through valve V3 into the reservoir. The valve V4 is closed during this period. On the reverse stroke, that is from left to right, the piston 148 exhausts surplus adhesive from the receptacle 54 through the valve V4, drawing it into the chamber 144 and the piston 150 draws a fresh supply of adhesive from the reservoir through the valve V2 into the chamber 146. During this time the valves V3 and V1 are closed.

The motor cylinder 166 is supplied with a suitable fluid pressure and a control valve is provided by means of which it may be manually operated or automatically operated in proper sequence with respect to the lasting operation. Injection should be timed so that it takes place while the ring is firmly in engagement with the bottom side of the upper.

To prevent damage to the apparatus in the event that the injection passage becomes blocked, a safety poppet-type of valve 178 is screwed into the injection passage 172'. Access to the several valves is afforded by valve covers 180, there being one such cover for each of valves V1 and V4 and one for the combined valves V2 and V3.

It should be understood that the present disclosure is for the purpose of illustration only and that this invention

includes all modifications and equivalents which fall within the scope of the appended claims.

I claim:

1. In a lasting machine, a bottom support upon which the bottom of an upper and insole assembled on a last are adapted to be held bottom down preparatory to lasting, a ring situated peripherally of the bottom support, said ring containing a groove designed to coincide with the marginal edge of the insole resting on the support and to which adhesive is adapted to be supplied for application to the insole, means supporting the ring for substantially universal movement relative to the marginal portion of the insole while the latter is resting on the bottom support to insure a seal between the upper surface of the ring and the margin of the insole while adhesive is being supplied to the groove for application to the margin of the insole in spite of imperfect clamping of the bottom to the bottom support, and a receptacle situated below the bottom support and ring for receiving the surplus adhesive from the groove, said receptacle containing an opening through which the adhesive collected therein may be withdrawn from the receptacle.
2. Apparatus according to claim 1, wherein said bottom support and ring have concave supporting surfaces for receiving the convex surface of the bottom at the forepart of the assembly.
3. Apparatus according to claim 1, wherein said support and ring collectively confront the forepart of the bottom from the tip to approximately the ball line, and said groove is spaced from the edge of the ring all the way around and has ends terminating substantially at the ball line in communication with the receptacle.
4. Apparatus according to claim 1, wherein the inner side of the ring is spaced from the bottom support to permit surplus adhesive to flow from the groove through said space to the receptacle therebelow.
5. Apparatus according to claim 4, wherein the receptacle contains a trough subjacent the space between the bottom support and ring, said trough encircling the bottom support and terminating at its ends in a well.
6. Apparatus according to claim 1, wherein the groove contains adjacent the toe injection openings through which adhesive is adapted to be delivered to fill the groove.
7. Apparatus according to claim 1, wherein the bottom support, ring and receptacle are inclined from the toe downwardly so that the adhesive in the groove gravitates toward the rear ends of the groove into the receptacle therebelow.
8. Apparatus according to claim 1, wherein the receptacle has a shallow trough situated below the bottom support and a deep well at the rear end into which the adhesive from the trough is free to flow.
9. Apparatus according to claim 1, comprising a post, and means adjustably mounting the bottom support on the post for adjustment of its level relative to the ring.
10. Apparatus according to claim 1, comprising a post, means adjustably mounting the bottom support on the post, and means yieldably mounting the ring and receptacle on the post around the bottom support.
11. Apparatus according to claim 1, comprising a post, containing a slot, a tongue to which the bottom support is secured, said tongue being adapted to be mounted in said slot, and means threaded through the tongue and bottoming in the slot operable to adjust the bottom support on the post.
12. Apparatus according to claim 1, comprising a post to which the bottom support is rigidly fixed, and wherein said means supporting the ring comprises a sleeve mounted on the post movable axially thereon to permit lowering of the ring relative to the bottom support, and wherein said ring is yieldably connected to its support for tilting movement about an axis coinciding with the median line of the bottom support and about an axis at right angles thereto.

13. Apparatus according to claim 1, comprising injection and exhaust pipes connected to the ring and receptacle, respectively, and a combination reservoir for adhesive and a pump associated therewith for effecting delivering of the adhesive to the injection pipe and extraction of the adhesive from the exhaust pipe, said combination reservoir and pump comprising a pair of pump chambers, each containing intake and discharge passage, a piston in each chamber, means connected to the pistons operable to reciprocate the pistons in unison in the same direction, and valves arranged in said passages so that as the pistons are moved in one direction adhesive in one pump chamber is discharged therefrom to the ring and adhesive in the other pump chamber is discharged into the reservoir, and so that on the reverse stroke adhesive is drawn from the ring into said other pump chamber and adhesive is drawn from the reservoir into the one pump chamber.

14. Apparatus according to claim 1, comprising injection and exhaust pipes connected to the ring and receptacle, respectively, and a combination reservoir for adhesive and a pump associated therewith for effecting delivery of the adhesive to the injection pipe and extraction of the adhesive from the exhaust pipe, said combination reservoir and pump comprising a pair of pump chambers, each containing intake and discharge passages, a piston in each chamber, means connecting the pistons operable to reciprocate the pistons in unison in the same direction, said passages comprising a passage from one pump chamber in communication with the ring, a passage from the other pump chamber in communication with the reservoir, said passages containing valves biased to open during movement of the piston in one direction, a passage from said other pump chamber in communication with the ring, and a passage from the one chamber in communication with the reservoir, said passages containing valves biased to open during movement of the pistons in the other direction.

15. Apparatus according to claim 1, comprising injection and exhaust pipes connected to the ring and receptacle, respectively, and a combination reservoir for adhesive and a pump associated therewith for effecting delivery of the adhesive to the injection pipe and extraction of the adhesive from the exhaust pipe, said combination reservoir and pump comprising a pair of pump chambers, each containing intake and discharge passages, a piston in each chamber, means connected to the pistons operable to reciprocate the pistons in unison in the same direction, said passages comprising, in one chamber, a discharge passage in communication with the ring containing a valve biased to open when the piston in said chamber is moving in one direction and an intake passage in communication with the reservoir containing a valve biased to close when said piston is moving in said one direction, and said passages comprising in the other chamber a discharge passage in communication with the reservoir containing a valve biased to open when the piston in said chamber is moving in said one direction and an intake passage in communication with the ring containing a valve biased to close when said piston is moving in said one direction.

16. Apparatus according to claim 1, comprising a post, a bracket mounted on the post, and means supporting the receptacle on the bracket comprising a plurality of rods, the ends of which are connected, respectively, to the receptacle and to the bracket.

17. Apparatus according to claim 16, wherein the upper ends of the rods are rotatably connected to the receptacle.

18. Apparatus according to claim 16, wherein the rods are arranged substantially symmetrically with one on the longitudinal center line near the toe and the other two at opposite sides of the center line near the ball.

19. Apparatus according to claim 18, comprising means non-yieldably securing the lower end of the one rod to

the bracket, and means yieldably securing the lower ends of the other two rods to the bracket.

20. Apparatus according to claim 16 wherein the rods are arranged substantially symmetrically with one on the longitudinal center line near the toe and the other two at opposite sides of the center line near the ball, and wherein the bracket contains openings for receiving the lower ends of the rods, a nut is mounted on the lower end of the rod at the toe in engagement with the top of the bracket to prevent downward displacement thereof, and a coiled spring is mounted on each of the other rods between the top of the bracket, and a nut threaded on the rod above the bracket for yieldably permitting downward displacement of said rods.

21. Apparatus according to claim 16, wherein the bracket is yieldably mounted on the post to enable lowering the receptacle and ring following application of adhesive to the margin of the insole to permit wiping the lasting margin of the upper inwardly between the adhesive-coated edge of the insole and the ring, into engagement with the adhesive-coated margin of the insole.

22. Apparatus according to claim 16, wherein the bracket is yieldably mounted on the post on the upper end of a spring coiled about the post with its lower end resting on a shoulder on said post, and there is an adjustable collar on the post above the bracket operable to fix the heightwise position of the bracket.

23. Apparatus according to claim 16, wherein a slot in the post and a pin on the bracket prevent rotation of the bracket on the post but permit yielding movement thereof.

24. Apparatus according to claim 1, comprising injection and exhaust pipes connected to the ring and receptacle, respectively, and a combination reservoir and pump, wherein the pump embodies two pistons operable in conjunction on one stroke to simultaneously eject a quantity of adhesive from one chamber to the ring and to return surplus adhesive from the other chamber to the reservoir, and on the other stroke simultaneously to take a fresh supply of adhesive from the reservoir into the chamber and to exhaust surplus adhesive from the reservoir into the other chamber.

25. Apparatus according to claim 24, wherein the pump has a discharge passage adapted to be connected to the injection pipe, and there is a safety valve in said injection passage in communication with the interior of the reservoir.

26. Apparatus according to claim 24, wherein the pump comprises two piston chambers containing pistons, said pistons being connected to a common crankarm, a pressure fluid operable motor operably connected to the crankarm to effect reciprocation thereof, and means for controlling the length of the stroke of the motor and in turn to control the stroke of the pistons.

27. Apparatus according to claim 24, wherein the pump is secured to the bottom of the reservoir by bolts extending through it from above the pump into the bottom, and wherein the bolts are of sufficient length that their upper ends are situated above the normal level of the molten adhesive to enable removing the bolts and hence the pump while the adhesive is molten.

28. In a lasting machine, a bottom support upon which the bottom of an upper and insole assembled on a last are adapted to be held bottom down preparatory to lasting, a ring situated peripherally of the bottom support, said ring containing a groove designed to coincide with the marginal edge of the insole resting on a bottom support and to which adhesive is adapted to be supplied for application to the insole, means supporting the ring for substantially universal movement relative to the marginal edge of the insole while the latter is resting on the bottom support to insure a seal between the upper surface of the ring and the margin during supply of adhesive to the said groove in spite of imperfect clamping of the shoe bottom to the bottom support, means mounting the last-named means on the bottom support for movement relative to the bottom support in a direction perpendicular to the

bottom to lower the ring from the marginal edge of the insole to enable wiping the lasting margin inwardly beneath the insole into engagement with the adhesive-coated margin, and a receptacle situated below the bottom support and ring for receiving the surplus adhesive from the groove while the ring is lowered, said receptacle containing an opening in which the adhesive collected therein may be withdrawn from the receptacle.

29. A lasting machine according to claim 28, comprising means for yieldably supporting said last-named means in engagement with the marginal edge of the insole, and means for limiting movement of the ring perpendicular to the bottom support in opposition to said yieldable means.

30. Apparatus for applying adhesive by means of an applicator to which adhesive is delivered from a reservoir and from which the excess adhesive is returned to the reservoir, comprising an applicator, a reservoir, a pump, and conductor means connecting the applicator to the pump and reservoir, said pump comprising a pair of pump chambers, each containing intake and discharge passages, a piston in each chamber, means connected to the pistons operable to reciprocate the pistons in unison in the same direction, said passages comprising a passage from the

5 discharge passage of one pump chamber in communication with one of the conductor means connecting the pump chamber to the applicator, a passage from the discharge passage of the other pump chamber in communication with the reservoir, said passages containing valves biased to open during movement of the pistons in one direction, a passage from the intake passage of the other pump chamber in communication with the conductor means connected to the applicator and a passage from the intake 10 passage of the one chamber in communication with the reservoir, said last two mentioned passages containing valves biased to open during movement of the pistons in the other direction.
